DESIGN FOR A MOP STICK

William E. Kautenberg, Freeport, Ill.

Application June 21, 1943, Serial No. 110,495

Term of patent 7 years

(Cl. D9—2)

To all whom it may concern:

Be it known that I, William E. Kautenberg, a citizen of the United States and resident of Freeport, in the county of Stephenson and State of Illinois, have invented a new, original, and ornamental Design for a Mop Stick, of which the following is a specification, reference being had to the accompanying drawing, forming a part thereof.

In the drawing, the figure is a perspective view of a mop stick showing my new design, a portion of the handle being omitted for convenience in illustration.

I claim:

The ornamental design for a mop stick, as shown.

WILLIAM E. KAUTENBERG.
